US00D911450S

(12) **United States Design Patent** (10) Patent No.: **US D911,450 S**
Peeters et al. (45) Date of Patent: **** Feb. 23, 2021**

(54) **GAME BOARD WITH GAME BOARD COVER AND GAME PIECES**

(71) Applicant: **SMART N.V.**, Kontich (BE)

(72) Inventors: **Raf Peeters**, Lier (BE); **Leighton Meredith Rees**, Cirencester (GB)

(73) Assignee: **SMART N.V.**, Kontich (BE)

(**) Term: **15 Years**

(21) Appl. No.: **29/688,148**

(22) Filed: **Apr. 18, 2019**

(30) **Foreign Application Priority Data**

Oct. 30, 2018 (EM) 005813094

(51) LOC (13) Cl. **21-01**
